G. C. TICHENOR

SOUND REPRODUCER

Filed July 31, 1922

Inventor
George C Tichenor
By Lyon & Lyon, Atty.

UNITED STATES PATENT OFFICE.

GEORGE C. TICHENOR, OF LOS ANGELES, CALIFORNIA.

SOUND REPRODUCER.

Application filed July 31, 1922. Serial No. 573,599.

To all whom it may concern:

Be it known that I, GEORGE C. TICHENOR, a citizen of the United States, residing at Los Angeles, in the county of Los Angeles 5 and State of California, have invented a new and useful Sound Reproducer, of which the following is a specification.

This invention relates to new and useful improvements in sound reproducing devices 10 and is adapted in general to any source of sound production which depends on the vibration or operation of a diaphragm for producing a reproducing sound. The invention is particularly useful in telephone 15 receivers, radio receivers and phonograph reproducers.

An object of this invention is to provide a means for absorbing any excessive vibrations which originate in or are imparted to the 20 sound producing diaphragm, and thereby to emit from the sound producer only a clear resonant tone.

In the common forms of sound reproducers, such as telephone receivers, phonograph 25 reproducers, there is more or less of what I refer to as excessive vibrations. These vibrations are in general due to imperfections in the repeating or reproducing device and generally manifest themselves as rattling, scratching or rasping sounds. These 30 vibrations are caused by a number of different means such as the over-charging of the receiver whereby the receiver cannot readily respond to subsequent vibrations due to the resiliency or tendency of the diaphragm to sustain the preceding vibration, or are caused by looseness or other mechanical defect of the receiver, whereby the diaphragm loosely rattles in the device, or are 35 in the case of a phonograph, by the sound producing diaphragm vibrating according to scratches or imperfections in the record.

My invention is adapted to eliminate these 40 excessive vibrations and has a very remarkable and pronounced effect upon the modulation and resonance of the emitted sound. Particularly in a receiver used in connection with the radio receiving device, there is a 45 large amount of these so-called excessive vibrations.

One of the objects of my invention is to 50 provide a radio loud speaker attachment, such as is used in connecting the conventional radio receiver to the horn of a phonograph which will emit the sound into the 55 horn in an exceptionally resonant tone.

Other objects of my invention will be more readily understood from the following drawings which illustrate a number of embodiments of my invention.

Figure 1 is an elevation partially in section of a radio loud speaker attachment embodying the principles of my invention.

Fig. 2 illustrates the embodiment of my invention in a conventional telephone receiver, said telephone receiver being shown partially in section to disclose the diaphragm sound producing mechanism.

Fig. 3 illustrates the embodiment of my invention in a phonograph reproducing device and is shown partially in section.

Referring to Fig. 1 of the drawings, 1 generally indicates a conventional radio receiver. 2 indicates an attachment case; 3 a clarifying diaphragm. As shown, the case 2 contains a cylindrical opening 4 adapted to be attached to the horn of a phonograph. The cylindrical opening 4 is provided with a screw 5 for securing the device to the horn. 6 indicates a clamping plate for holding the 25 radio receiver in the case and 7 indicates screws for maintaining the clamping plate on to the case. The case 2 is properly recessed as indicated at 8 to contain the expanded portion of the radio receiver and 30 further recessed as indicated at 9 for supporting the clarifying diaphragm 3. The diaphragm 3 is held in the case by means of two rubber cushions 10 which consist of small rubber tubing. The radio receiver is 35 clamped against these rubber cushions 10 thereby holding the clarifying diaphragm 3 in place.

The clarifying diaphragm 3 is preferably composed of pure mica, although other materials may be used. It should contain an aperture 11 which aperture is preferably substantially equal and similar to the aperture 12 in the radio receiver. 13 indicates the customary sound producing diaphragm 40 operated as usual by electro-magnetic means 14.

In use the attachment is secured to the horn of a phonograph by means of the screw 5, the cylindrical opening 4 surrounding the 45 contracted end of the phonograph. The electrical current generated or received in the wireless receiving system will cause the diaphragm 13 to vibrate, emitting sound through the aperture 12, which in turn, 50 causes the clarifying diaphragm to vibrate which diaphragm will be found to absorb

any excessive vibrations from the producing diaphragm 13 and to emit the sound to the horn in a remarkably clear and resonant tone.

5 In Fig. 2 I have illustrated the embodiment of my invention in a telephone receiver wherein it operates substantially similar to the operation of the radio loud speaker attachment and absorbs the excessive vibrations and increases the clearness or resonance of the emitted sound. The receiver up to and including the sound producing diaphragm 13 may be similar to the construction now in use and need not be here described. In the casing of the receiver, I have provided a restricting member 15 containing an aperture 12. The aperture 12 is preferably equivalent in size to the apertures of the usual receiver. This restricting member 15 is shown screw-threaded into the case of the telephone receiver and holds the producing diaphragm 13 in place. Attention is directed to the fact that the restricting member 15 is not a diaphragm, i. e. of the requisite character to respond to frequencies of vibration such as result in sound. The member 15 acts to restrict the emission of the sound vibrations from the sound producing diaphragm to the aperture of the restricting member so that all sound passing by such member 15 must pass through the aperture 12 thereof. The clarifying diaphragm 3 is maintained adjacent the restricting member 15 and contains an aperture preferably substantially equal to the aperture of the restricting member 15. The clarifying diaphragm 3 is provided with two rubber cushions 10 similar to those shown in Fig. 1. The cover plate 16 is 40 slightly larger than usual to enclose the restricting member 15 and clarifying diaphragm 3 and maintains these parts in position as shown in Fig. 2.

45 Referring to Fig. 3 of the drawings, I have shown an embodiment of my invention in the sound producing equipment of a phonograph. The needle mechanism of the producing diaphragm is made of any of the preferred constructions which are well

known in the art and need not here be described. 13 indicates the sound producing diaphragm. Interposed between this diaphragm and the horn is provided a restricting member 15 having an aperture 12. A clarifying diaphragm 3 is maintained adjacent the restricting member 15 in a suitable recess in the device and is held between two rubber cushions 10. These cushions are similar to the others described. The clarifying diaphragm 3 contains an aperture 11 55 preferably substantially equal and similar to the aperture 12 in the restricting member 15. It will be found by this combination that the sound emitted from the phonograph will be markedly improved in the quality or 60 modulation of the tone and that a large number of the rasping or rattling sounds will be eliminated.

65 As can be seen from the foregoing description, my invention consists primarily in combining with a sound producing diaphragm a second or clarifying diaphragm which clarifying diaphragm is capable of absorbing from the producing diaphragm the afore-mentioned excessive vibrations and 70 of emitting the sound in a clear resonant tone. My invention is capable of being embodied in a number of different ways and applied in a wide number of different instruments. It is understood, therefore, that 75 my invention is not limited to the embodiments shown but is of the scope set forth in the following claim.

I claim:

80 In a sound producing device, the combination of a container, a diaphragm rigidly mounted therein, a stiff sound restricting member rigidly mounted adjacent thereto and having a single central aperture through 85 which the vibrations of the producing diaphragm are emitted, and a clarifying diaphragm having a single aperture aligned with and of equal diameter to the first of said apertures, and adapted to absorb vibrations 90 of the sound producing diaphragm.

95 Signed at Los Angeles, California, this 25th day of July, 1922.

GEORGE C. TICHENOR.
